UNITED STATES PATENT OFFICE.

GUSTAVUS MILLHISER, OF RICHMOND, VIRGINIA, ASSIGNOR TO THE
MILLHISER MANUFACTURING COMPANY, OF SAME PLACE.

DESIGN FOR A TOBACCO-PACKAGE.

SPECIFICATION forming part of Design No. 29,850, dated December 20, 1898.

Application filed November 26, 1898. Serial No. 697,561. Term of patent 14 years.

To all whom it may concern:

Be it known that I, GUSTAVUS MILLHISER, a citizen of the United States, residing at Richmond, in the county of Henrico and State of Virginia, have invented and produced a certain new and useful Design for Tobacco-Packages, of which the following is a specification, in which—

Figure 1 is a perspective view, and Fig. 2 a plan view, of the package.

My design consists of a cloth or textile package having a square substantially flat base *a* and a square substantially flat top *b*, the four flat sides *c* extending at right angles to each other and to the upper and lower faces. On the upper face is formed a series of radiating

plaits or folds *d*, which extend from a central opening *e* to the edge of the package, forming a sort of rosette, and over the opening is a bow-knot *f*. The package is substantially 20 the same vertical thickness throughout, the upper and lower faces being substantially parallel.

I claim—

The design for a tobacco-package substantially as herein shown and described.

In testimony whereof I affix my signature in presence of two witnesses.

GUSTAVUS MILLHISER.

Witnesses:

C. D. DAVIS,
Wm. R. DAVIS.
